(57) **CLAIM**

The ornamental design for a payment kiosk as shown and described.

DESCRIPTION

FIG. 1 is a front, upper, right perspective view of a payment kiosk of our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dash-dash broken lines represent unclaimed portions of the payment kiosk and form no part of the claimed design. The dash-dot broken lines define bounds of the claimed subject matter and form no part of the claimed design.

1 Claim, 7 Drawing Sheets(56)
